UNITED STATES PATENT OFFICE.

ROBERT D. HAINES, OF CORNING, NEW YORK, ASSIGNOR TO THE CORNING GLASS WORKS, OF SAME PLACE.

MARINE LENS.

SPECIFICATION forming part of Letters Patent No. 447,727, dated March 3, 1891.

Application filed September 13, 1890. Serial No. 364,844. (No model.)

To all whom it may concern:

Be it known that I, ROBERT D. HAINES, a citizen of the United States, residing at Corning, in the county of Steuben and State of 5 New York, have invented certain new and useful Improvements in Marine Lenses; and I do hereby declare the following to be a full, clear, and exact description of the invention, such as will enable others skilled in the art 10 to which it appertains to make and use the same.

My invention relates to improvements in marine lenses, or in lenses of that class which is designed for signaling; and the object of 15 my improvement is to provide a lens superior to those of said class now in use in the following particulars, namely: It is a lens more easily manufactured, more perfect in construction, with an equal amount of strength 20 in the projection of the light. It is protected from blows on the zones, and is therefore more durable, and when flashed a much better piece of work. It can be fire-polished to a much better advantage, and it is novel in construction, as will be hereinafter pointed out in 25 the claims. I attain said object by a novel construction fully described in this specification and illustrated in the accompanying drawings, in which—

30 Figure 1 is a perspective view of a section of my lens. Fig. 2 is a view of my lens in a cylinder form.

A designates a cylindrical lens, which may be constructed in sections or segments a , or 35 in a complete cylinder, as desired. The concave or inner surface a' is divided into zones 1, 2, and 3. The zones 1 and 2, respectively, are provided with the angular or prismatic horizontal grooves or furrows a^2 . The central zone 3 is convex transversely and has a 40 smooth surface. The outer or convex surface a^3 of the lens is likewise smooth.

As my invention pertains to the mechanical novelty and the improved results arising 45 therefrom both mechanically and optically, which will be hereinafter set out, it would be useless to enter into an explanation concerning the optical principle which applies to the construction and arrangement of said 50 zones. Suffice to say to any one familiar with

optics it will be readily observed that they are in accordance with scientific principles and the laws of reflection and refraction.

I attach special importance to my invention for the following reasons:

55

First. The lens is more likely to be perfect in construction for the reason that in annealing it will not get out of shape so readily as the old design.

Second. It is a much better piece of work 60 when flashed, because the concentric circles that form on the old style of lens in molding can be fire-polished away. In the old style of lens the zones, being molded upon the outside surface, causes an almost infinite number 65 of concentric circles, which look like cracks, to appear embedded in the glass upon the inner side of the lens. This is very detrimental to the lens from an optical standpoint and interferes with the rays of reflection and refraction, thereby destroying the 70 efficiency of the lens for the purpose designed. As these concentric circles are upon the inner side of the lens, which is cylindrical in form, it is impossible to reach the same 75 with a view of fire-polishing them away. By “fire-polishing” I mean exposing to a very hot or rosin fire, which melts off all uneven surfaces and makes the surface exposed susceptible of a very high degree of reflection. 80

It is evident that as the zones in the old style of lens were formed upon the outside surface it would be impossible to expose the same to fire without melting away and destroying the 85 efficiency of the prismatic grooves or furrows, which would of course render valueless the lens. This, then, is one of the main advantages of my lens over the old style, and it is obvious that it produces a decidedly improved result, not only mechanical but optical. 90

Third. Another important result mechanically is accomplished by having the zones 1 2 3 upon the inner or concave side, because said zones are thereby protected from blows which occasion chipping and fractures, often 95 destroying completely their efficiency. By having the zones on the inner side only the smooth surface is exposed.

What I claim as new, and desire to secure by Letters Patent, is—

100

1. A cylindrical lens having a smooth outer surface provided upon its concave or inner surface with the angular or prismatic horizontal grooves or furrows, substantially as described, and for the purpose set forth.
2. A section of a cylindrical lens having a smooth outer surface, provided upon its concave or inner surface with the angular or prismatic horizontal grooves or furrows, substantially as described, and for the purpose set forth.
3. A cylindrical lens or section having a smooth outer surface, provided upon its con-

cave or inner surface with the horizontal zones 1 2 3, the zones 1 and 2 having the angular or prismatic horizontal grooves or furrows and the zone 3 being transversely convex and smooth, substantially as described and set forth.

In testimony whereof I affix my signature in presence of two witnesses.

ROBERT D. HAINES.
